[57] CLAIM

The ornamental design for a cereal piece, as shown.

DESCRIPTION

FIG. 1 is a top plan view of a cereal piece, showing our new design;

FIG. 2 is a first side elevational view thereof;

FIG. 3 is a second side elevational view directly opposing said first side elevational view;

FIG. 4 is a third side elevational view orthogonal to said first side elevational view; and,

FIG. 5 is a fourth side elevational view directly opposing said third side elevational view.

FIG. 1

FIG. 2

FIG. 3

FIG. 4

FIG. 5
